UNITED STATES PATENT OFFICE.

EDWARD H. SHORE, OF HEREFORD, TEXAS.

GAME.

Application filed July 7, 1923, Serial No. 650,058. Renewed July 16, 1927.

This invention relates to an improved game played with cards, the general object of the invention being to provide the cards with representations of horse shoes and pegs 5 so that a game, simulating the game of pitching horse shoes, can be played with the cards.

Another object of the invention is to so arrange the pictures on the cards that every 10 score that it is possible to make with two horse shoes is shown on the cards, thus permitting persons who are fond of the game of pitching horse shoes to play the game with the cards when it is impossible to play the 15 real game and the cards will also teach the real game of pitching horse shoes.

This invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying 25 drawings wherein like characters denote like or corresponding parts throughout the several views, and in which:—

Figure 1 is a face view of No. 0 card which 30 is called the "outlaw" card.

Figures 2 to 14 are face views of the other cards of the set.

Figure 15 is a view showing the rear face of the cards.

As shown in these views the face of each 35 card has printed, or otherwise placed thereon, two representations of a pair of horse shoes, a post and a circular member which is divided into an inner circle and an outer 40 one. The horse shoes are indicated by the reference character 1, the post by the reference numeral 2 and the inner circle is shown at 3 and the outer circle at 4. Each card has its designating numeral in the upper left 45 hand corner and the lower right hand corner, as indicated at 5, and the number of points scored by each card is printed between the two representations or pictures, as shown at 6. The cards show the horse shoes in dif- 50 ferent positions and the cards represent the shoes in all positions that a pair of horse shoes can assume in playing the real game of horse shoes. Figure 1 shows the zero card, designated "outlaw", with the horse shoes 55 in the outer circle. Thus no score is made

when the shoes are in this position. Figure 2 shows the No. 1 card with the horse shoes ringing the post, this card giving the highest number of points which is 10. Figure 3 shows the No. 2 card, the horse shoes ringing the post but one of them is upside down so that this is a scratch ringer and only gives 60 eight points. Figure 4 is a view of the 3rd card which shows a ringer and a leaner so that this card represents eight points. Figure 5 is a view of the fourth card showing a ringer and a close shoe which gives six points. Figure 6 is a view of the fifth card which shows a double scratch ringer which gives six points. Figure 7 is a view of the 70 sixth card which shows a scratch ringer and a leaner which gives six points. Figure 8 is a view of the 7th card which shows a ringer and a foul shoe which gives five points. Figure 9 is a view of the 8th card 75 which shows a scratch ringer and a close shoe, giving four points. Figure 10 is a view of the 9th card which shows a leaner and a close shoe giving four points. Figure 11 is a view of the 10th card which shows 80 a scratch ringer and a foul shoe which gives three points. Figure 12 is a view of the 11th card which shows a leaner and a foul shoe giving three points. Figure 13 is a view of the 12th card which shows two close shoes 85 giving two points. Figure 14 is a view of the 13th card which shows a close shoe and a foul one giving one point. Figure 15 is a view showing the back of the cards.

The pack contains 52 scoring cards and 90 one outlaw card, the scoring cards consisting of four sets, each set containing 13 cards numbered or ranked from 1 to 13.

From the foregoing it will be seen that this game will simulate the real game of 95 pitching horse shoes so that persons fond of this sport can play the card game when it is impossible to play the real game. These cards will also teach one how to play the real game. While the game can be played 100 in any way desired, I prefer to play it under the following rules:—

Dealing.—Begin with first player to left, deal twelve cards to each player, three cards at a time, the remaining cards shall lay face 105 down on the table and shall not be exposed.

Objects of game.—To hold in hand highest ranking cards, to take in tricks, to make highest score, to tie score of opponent.

The play.—Bidding for first play: Bid- 110

ding begins with first player to left of dealer, and rotates to the left, (each player naming the number of points he offers to make) player not wishing to bid may pass, each player is allowed one bid only and must bid higher than preceding player or pass, the highest bid has first pitch, and must score as many points as he bid.

If bidder fails to score as many points as he bid, or offered to make, he has "fouled", and his opponent will score the number of points bid.

If any player shall foul three times during the progress of the game, he has "fouled", the game, and his opponents shall be declared winners of the game.

If no bid is made, oldest hand has first pitch.

Player securing first pitch, may play any card in his hand, (although it is the rule of the game that each player will make the best pitch possible at each play). The play continues to the left, and each player in turn should try to defeat or tie the play of his opponent.

Highest pitch made wins the trick, unless two pitches of the same rank are made by opponents, then, the next highest pitch wins the trick.

Scoring.—Points are counted according to rank or value of the pitch, that is, if first player pitch a "double ringer" and second player pitch a "double scratch ringer", then third player pitch a "fair ringer and a close shoe" then fourth player pitch a "fair ringer and a leaner" first player wins the trick and scores, two points.

If first player pitch a fair ringer and a foul shoe he scores five points, then second player pitch a scratch ringer and a close shoe, and scores four points, then third player pitch two close shoes, and scores two points, and fourth player pitch a leaner and a foul shoe and scores three points, the partners have scored an equal number of points in value, the first player having made the pitch of highest rank wins the trick and no score is counted.

In a four handed game the score of partners shall be added, and the highest score wins the trick, and the partner playing making the pitch of highest rank has first pitch.

Score will always be counted according to the difference in value of the pitch. In case of a tie, the pitch of highest rank wins the trick.

All equals shall be counted as ties, that is, if two contestants make a pitch of equal rank and value they are tied, and the one making the next highest pitch wins the trick and is entitled to score the difference between

the value of his pitch and that of his opponent.

If all contestants make a pitch of equal value, no score will be counted, but the player making the pitch of highest rank—that is not tied by his opponent—wins the trick, and shall have first pitch,—that is: if two players pitch double scratch ringers, one a scratch ringer and a leaner, and the other a perfect ringer and a close shoe,—the perfect ringer wins the trick,—but no score is made.

The contestant first scoring 21 points wins the game.

Score may also be made by counting tricks instead of points, contestant winning the greatest number of tricks, shall score "two" points for each trick taken in excess of opponent, that is: if one contestant shall win five tricks, and the other seven tricks, the contestant winning seven tricks shall score "four" points.

What I claim is:—

1. A card game of the class described comprising a number of cards, each having thereon a representation of a post and a pair of horse shoes, the horse shoes being arranged in different positions relative to the post on the cards so that the cards will show all the scores that it is possible to make in a real game of horse shoes.

2. A game of cards comprising a number of sets of cards, each set consisting of thirteen cards and each card having thereon the representation of a pair of horse shoes and a post, the horse shoes being differently arranged on the cards to give the different scores.

3. A game of cards comprising a number of sets of cards, each set consisting of thirteen cards and each card having thereon the representation of a pair of horse shoes, and a post, the horse shoes being differently arranged on the cards to give the different scores and an outlaw card for the deck.

4. A pack of cards for playing a game of horse-shoes, comprising one or more series of cards, said cards illustrating the various positions taken by a pitched horse-shoe.

5. A horse-shoe card game, having cards comprising two or more suits, the cards in each suit representing the distances horse-shoes may lie from a pitching stake after being pitched.

6. A pack of cards for playing the game of horse-shoes, comprising one or more series of cards, certain of said cards representing the various distances a pitched horse-shoe may lie from a pitching stake, and others representing ringers.

In testimony whereof I affix my signature.

EDWARD H. SHORE.
